UNITED STATES PATENT OFFICE.

SOLOMON KARPEN AND FRANK KASPAR, OF CHICAGO, ILLINOIS, ASSIGNEES TO
S. KARPEN & BROS., OF CHICAGO, ILLINOIS, A CORPORATION OF WEST VIRGINIA.

UPHOLSTERED FURNITURE AND METHOD OF PRODUCING THE SAME.

Application filed July 16, 1923. Serial No. 651,790.

This invention relates particularly to the production of upholstered furniture, such as chairs, sofas, settees, and so forth.

The primary object is to reduce the cost of manufacturing upholstered furniture, without detracting from the appearance and quality of the upholstered article.

The method of upholstering chairs, sofas, settees, footstools and so forth which has been in common use for very many years, requires a high degree of skill, is laborious, and is unnecessarily expensive. For example, according to a known method, a chair frame is equipped with upholstery springs, mounted, tied and covered in any suitable manner, as for example in the manner illustrated in the lower structure shown in Fig. 7 of the accompanying drawings, a piece of burlap being placed over the springs and nailed to the frame members; a layer of cotton wadding is then placed on the burlap; a muslin envelope of suitable size is filled with suitable cushioning material, which may comprise springs, hair, cotton or other filling, the cushion thus formed being placed over the cotton layer and the envelope tacked at its edge portions to the frame; hair, cotton or moss or other suitable filling, is placed on top of the cushion referred to and is stitched down to shape, a cover of muslin being applied and the last mentioned filling being suitably shaped within said cover, the edges being squared or rounded off to fit the chair and according to the style, the edges of the muslin being pulled down and tacked to the frame, a finishing cover is then tacked to the frame and drawn snugly over the structure and nailed at its edges to the frame; and a welt is tacked over the edges of the cover to conceal the tacks used in securing the finishing cover; a band of finishing covering, cut to size, is tacked through the welt on to the frame (blind tacked) and this band is pulled down and the edge tacked under the rail of the frame. Should the style of the chair call for an exposed finished wood frame, the finishing cover is tacked in a rabbet at the upper edge of the rail and a guimpe is glued or tacked over the raw edge, thus finishing the job.

It will be understood by those skilled in the art and in the example given, that the work of building up the seat above the sub-structure of spring work is not only labori-

ous, but requires a skilled workman to properly shape the cushion and produce a workmanlike job.

According to the improved method illustrated and described herein, the cushion is formed in a suitable stuffing machine and applied to the frame in a manner which obviates the necessity of "building up" a cushion on the frame of the article of furniture, and this is accomplished without sacrificing any of the desirable qualities of furniture made in accordance with the known methods. Thus, the improved method largely obviates the very laborious portion of producing an upholstered job, renders unnecessary the use of that degree of upholstering skill which is acquired only by years of practice, enables a uniform product to be produced by means of less highly skilled labor, and greatly cheapens the cost of manufacture.

The invention is illustrated in the accompanying drawings, in which—

Fig. 1 represents a broken vertical sectional view of a cushion stuffing machine; Fig. 2, a transverse sectional view taken as indicated at line 2 of Fig. 1; Fig. 3, a broken vertical sectional view of a chair or a settee constructed in accordance with one species of the invention; Fig. 4, a similar sectional view embodying another species of the invention; Fig. 5, a special perspective view of the envelope employed in the construction shown in Fig. 4, the dotted lines at the right hand portion of the figure illustrating the manner in which the end of the envelope is left open for the stuffing operation; Fig. 6, a special view of an upholstered cushion provided with skirts and rendered to be applied to the frame of a chair or other article of furniture; Fig. 7, a broken vertical sectional view of a chair or other article of furniture, showing the skirted finished cushion applied to a frame having a sub-structure or bottom embodying upholstery springs; Fig. 8, a perspective view of a chair constructed in accordance with the invention employing the skirted finish cushions for both seat and back; Fig. 9, a broken perspective sectional view illustrating the manner in which the seat-cushion is secured to the frame; Fig. 10, a similar view, showing a modified method of securing the cushion and finishing the upholstery work; Fig. 11, a broken perspective sectional view showing a modified method of applying the fin-

ishing skirt; and Fig. 12, a broken perspective sectional view showing another modification, illustrating a method of applying the finish cushion to a frame which has an exposed finish surface.

Referring to Figs. 1, 5 and 6, A represents the envelope or cushion; and B, the filling of the cushion, which comprises, in this case, a spring structure B' mounted on a wooden frame B², and a layer of cotton or suitable wadding B³.

The envelope A has a bottom 1, which may be formed of canvas or other suitable strong fabric, this bottom being provided at its edges with a depending skirt 1^a. The envelope has a top 2, which may be of mohair, plush or any other suitable covering material, adapted to serve as a finish covering; the envelope has side portions 2^a of the same material, and has the skirt 2^b, which also is preferably of a finish fabric. In shaping the envelope, welts may be formed, as at 3 and 4. In the illustration given, the welt 3 is shown as formed by folding the side fabric 2 at its upper edge, the welt being then joined to the edges of the top fabric 2 by means of stitches 5; also, the welt 4 is shown as formed at the upper edge of the skirt 2^b, and the welt thus formed is sewed to the lower edge portion of the side strip 2^a and to the upper portion of the inner skirt 1^a, as by stitches 6.

As shown in Fig. 1, the envelope is preparatorily formed and stitched, but is left open at one end, and the end flap thrown up. Also, adjacent the open end, the lateral side strips 2^a are left for a short distance unconnected with the bottom fabric 1. That is, in forming the envelope preparatorily, one end of the finish fabric is left without being sewed to the bottom fabric and the lower edges of the lateral side strips of the finish fabric are left unsewed to the bottom fabric for a short distance. This enables the envelope to be slipped on to the chute C' of the stuffing machine C. The stuffing machine, or cushion forming machine, may be of any suitable construction. Such machines are known, and need not be described in detail herein. The machine is provided with a longitudinal passage or way C² in which the stuffing or cushion material B is placed. The passage C² has a top wall C³, which may be raised to enable the cushioning material to be introduced. Also, the chute C' tapers longitudinally, and comprises two telescopic U-shaped sections 7 and 8, as shown in Fig. 2. The upper section 7 is secured to the member C³, and the lower section 8 is bolted, as at 9, to the main frame 10. A follower C⁴, actuated by an endless chain C⁵ in a well known manner, serves to expel the cushioning structure B from the way and force it through the tapered chute C' into the envelope of the

cushion, it being understood that an attendant holds the envelope in position during the stuffing operation, gradually allowing the envelope to be forced off the chute. After the stuffing operation, the filled envelope is withdrawn, and the open portions are sewed together, thus completing the cushion.

It will be noted from Fig. 6 that the frame B² is "sprung" in a manner known to the upholstery art. That is, the frame is equipped with a suitable spring-foundation 11, which may comprise rods or any other suitable material; the upholstery springs 11^a are mounted on said foundation; the springs are tied by cords 11^b in the usual manner; and a burlap cover 11^c is placed over the springs and tacked to the frame. Thus, the wadding, such as cotton batting or the like, B³, may be placed upon the spring structure without danger of working into the springs. The spring structure may be provided with a spring edge 11^d, as shown in Fig. 6.

The finished cushion, constructed as illustrated in Fig. 6, may be applied, for example, to the seat frame D' of a chair D, as shown in Fig. 4. In this figure, the finished cushion is of the same construction as that illustrated in Fig. 6, except that the form of the wooden frame B² is slightly modified, and is here designated B³. The other parts of the cushion are the same as shown in Fig. 6, and are designated by the same reference characters. Still referring to Fig. 4, the finished cushion is placed in position in the chair with the wooden frame B³ resting on the seat frame D'; the short inner skirt 1^a is drawn down over the upper portion of the outer surface of the seat frame D' and is secured to the seat frame by tacks 12. The outer, or finish fabric skirt 2^b is drawn down to cover the outer surfaces of the rails of the seat frame and is secured to the lower edges of the rails by tacks 13. Where desired, cotton batting or other suitable stuffing material 14 is introduced between the skirt portion 2^b and the rail of the seat frame of the chair.

Referring to Fig. 3, E represents the frame of a chair or other article of furniture, and E' represents the seat frame which forms a part of the structure.

F represents a finished cushion which is formed in the manner described with reference to the cushion shown in connection with the article of furniture depicted in Fig. 4, except that the skirts are omitted from the finished cushion. In Fig. 3, the article of furniture is designed to have the outer surfaces of the rails of the seat frame E' present finished wood surfaces. The seat frame is therefore formed as a socket to receive and house the lower portion of the cushion structure. The cushion is shown as com-

prising an envelope 15 having top 15^a, and side strips 15^b made of finish fabric and having a bottom 15^c of canvas or other suitable strong, comparatively cheap fabric. The lower edges of the side strips 15^b are sewed to the edge portions of the bottom 15^c, as indicated at 15^d. The cushioning structure which is enclosed within the envelope 15 comprises a wooden frame 16, equipped with a suitable rod or wire foundation, 16¹; upholstery springs 16^b supported on the foundation, cords 16^c securing the springs in position; a burlap cover 16^d over the springs and secured to the inner frame 16; and a layer of cotton or other suitable wadding material 16^e over the burlap. The stuffing operation is effected in the manner already described with reference to the cushion structure shown in Figs. 4 and 6. All that is necessary to effect the upholstering of the chair, after preparing the cushion, is to insert the cushion in the frame, the lower portion of the cushion structure being supported on and housed within the seat frame E'. This seat frame is shown as comprising the exposed rails 17 and inner corner braces 17^a which are rigidly secured to the lower portion of the rails. The inner frame 16 rests upon the corner braces 17^a and is secured thereto by means of screws 18. Thus, the proper upholstering of an article of furniture of this design is effected by simply inserting the finished cushion in the socket provided by the seat frame and attaching the inner frame with which the cushion is provided to the seat frame by means of screws, or the like.

Referring to Fig. 7, G represents the frame of a chair or other article of furniture which is provided with a seat frame G', a spring structure G² built within said seat frame, a back G³, and arms G⁴; and, in addition, a finished seat-cushion H and a finished back cushion H', preparatorily constructed, and applied to the frame of the article of furniture.

The cushion H is, in this instance, shown as comprising a fabric casing or envelope 19, and cushioning material 20 with which the envelope is stuffed. The seat frame of the article of furniture is "sprung", or provided with a spring structure G² according to well known practice, and need not be described in detail. It affords a deep spring structure which is surmounted by a seat-cushion H. The envelope 19 comprises the canvas bottom member 19^a and top member 19^b, side strips 19^c and outer skirts 19^d of finish fabric. The canvas 19^a has its marginal portions affording a relatively short skirt 19^e, which is secured to the upper portion of the seat frame G' by means of tacks 21. The outer skirts are secured to the lower edge of the seat frame by tacks 22. The stuffing 20 comprises layers of cotton batting or

other suitable filling material 20^a and 20^b and a spring structure 20^c which may be a spring structure of the Marshall type, that is, a fabric envelope provided with individual pockets containing coil springs, as is well understood in the art. In the construction here being described, it will be noted that the inner skirt 19^e has its back flap extended and tacked beneath the rear rail of the seat frame, while the back flap of the outer skirt is omitted. This expedient may be employed where it is not important to use finish fabric at the rear of the article of furniture.

Still referring to Fig. 7, the back cushion H' is formed independently, and then applied to the back frame G³. In this case, a sufficient foundation is provided on the back frame by tacking a strong sheet of fabric 23, such as canvas or burlap to the front surfaces of the rails comprising the back frame. The cushion H' comprises an envelope 24 and stuffing 24^a, which may consist of springs and suitable wadding, such as cotton batting, hair or moss. The envelope 24 is formed with flaps or skirts 24^b, which are drawn over the frame and tacked thereto. At the sides and top of the back frame, the skirt flaps may have their margins tacked to the back surface of the frame member, as by means of tacks 25. The lower flap may be tacked to the underside of the lower cross member of the back frame G³ by tacks 26.

Thus it will be understood that the structure shown in Fig. 7 is made to present a finished upholstered appearance and to possess the durability and luxurious qualities of an article of furniture upholstered in the ordinary way by the simple expedient of providing previously stuffed cushions and applying them in the manner described. Indeed, an article of improved appearance and uniformity can be provided by means of the improved method and without the use of highly skilled labor, inasmuch as the proper proportioning, shaping and balancing of the upholstering materials is provided for by employing correct patterns for the cushion envelopes, and effecting the stuffing of the envelopes by a labor-saving machine.

Referring to Figs. 8 and 9, I represents a chair having a seat-cushion I' and a back cushion I² applied thereto by means of the improved method. In this case, the seat frame 27 has built therein, in the usual manner, a spring structure 27^a, which is covered with burlap 27^b. The seat-cushion I' has an envelope 28 comprising a canvas base 28^a, which affords an inner skirt 28^b; and the seat-cushion has its top 28^c, its side strips 28^d and its skirts 28^e formed of finish fabric. The stuffing of the seat-cushion is designated 29 and is composed of springs and other suitable stuffing material in the same manner as the seat-cushion H shown in Fig. 7. The inner, short skirt 28^b is se-

cured to the outer surfaces of the seat by tacks 30, and the outer skirt has its lower margin secured by tacks 31 to the lower edges of the members of the seat frame. 5 Wadding 32 is interposed between the skirt 28^e and the members of the seat frame. The back cushion I² may be formed and applied in the same manner as the cushion H² shown in Fig. 7. It will be noted that 10 the chair shown in Fig. 8 is provided with arms 33, whose front ends are supported on rounds 33^a, secured to the sides of the seat frame. The arms are suitably covered, as indicated in the drawing; and the seat-cushion 15 I¹ and back cushion I² are recessed, as indicated at 34 and 35 to accommodate, respectively, the rounds 33^a and the rear end of the arms 33.

The construction shown in Fig. 10 is similar to the construction shown in Fig. 9, except that the outer skirt 28^f is not attached by lines of stitching. In this case, the side strip 28^d is provided with an extension 28^e; and a tacking strip 36 and tacks 36^a are employed to secure a down-turned margin 28^h of the skirt 28^f, the extension 28^e, and the inner skirt 28^b to the seat frame 27. The lower margin of the outer skirt 28^f is tacked to the lower edge of the seat frame in the manner illustrated in Fig. 9.

Referring to Fig. 11, the figure shows a modified method of applying the outer skirt to the cushion. In this figure, J represents a frame of an article of furniture, such as the seat frame which is "sprung" or equipped with a spring structure J¹ built therein in the usual manner, the spring structure having in this case a "spring edge" or marginal rod J² disposed some distance 40 above the frame member J. The cushion K is formed independently, as has been described with reference to the other structures. In this case, the cushion has an envelope comprising a canvas base 37, whose 45 margin affords an inner skirt 37^a; and the cushion envelope has the top member 38 and the side strips 38^b of finish fabric. The outer skirt 38^b and welt 38^c are formed of finish fabric and the welt portion is connected with the previously applied cushion 50 and with the marginal rod J² of the spring structure by means of a lacing, or heavy thread 39. The inner skirt 37^a is secured to the frame J by tacks 40, and the lower margin 55 of the outer skirt 38^b is secured to the lower edge of the frame member J by means of tacks (not shown) in the same manner as the skirt 28^e is secured in Fig. 9.

Referring to Fig. 12, L represents a 60 frame, such as a seat frame, and M represents a preparatorily formed cushion. The frame L has, in this case, an outer finish surface 41, and a rabbet 41^a at the upper portion. The cushion M comprises an envelope having a base fabric 42, a top fabric

42^a, an inner side flap 42^b which may be of canvas, and an outer side fabric 42^c of finish fabric. The members 42^b and 42^c are extended to provide rudimentary skirts 42^d. These rudimentary skirts are secured in the rabbet 41^a by means of tacks 43, and these tacks and the margins of the skirts are concealed by a guimpe 44 which may be glued in position, or secured by finish tacks 45. The cushion M is formed by stuffing a frame supported spring structure 46 and wadding 46^a in the envelope described. The cushion is then applied to the frame in the manner described. This is another instance of applying a preparatorily formed cushion to a frame which is provided with a finish outer surface, rudimentary skirts being preferably employed in this case in connection with a rabbet to receive the skirts and the finishing guimpe. This may be compared with the construction shown in Fig. 3, where the lower portion of the cushion structure is simply received in a socket formed by the seat frame of the article of furniture, the inner frame being secured to the seat frame 80 by screws or the like. In the construction shown in Fig. 12, the cushion is secured by the rudimentary skirts and tacks. These skirts may be very short, or may even be omitted in a construction of the character shown in Fig. 12, in which case the lower corners of the envelope of the cushion would be stretched down into the rabbet and tacked therein, and the concealing guimpe then applied.

It will be noted that in all of the constructions described, previously stuffed cushions are employed, and provision is made for so applying the cushions to the frame of the article of furniture as to secure the effect of an upholstering job performed according to known methods. That is, all of the durable and luxurious qualities of the old method of upholstery are retained in the practice of the new method, but by the new method greater uniformity is secured, the use of highly skilled labor is rendered unnecessary, and the expense of producing a properly upholstered article is greatly reduced.

The foregoing detailed description has been given for clearness of understanding only, and no unnecessary limitations should be understood therefrom, but the appended claims should be construed as broadly as permissible in view of the prior art.

What we regard as new, and desire to secure by Letters Patent, is:

1. An article of furniture comprising a frame and a separately formed cushion secured in said frame, said cushion comprising a permanently closed envelope having an upper side and edge portions of finish fabric and cushioning means completely sealed in said envelope, said cushioning

means including a spring structure carried by a wooden frame mounted on said first-named frame to form therewith an upholstered article of furniture, the fabric of said envelope extending between said main frame and the frame of said spring structure.

2. An article of furniture comprising a seat frame provided at the upper portion of its outer surface with a rabbet, a separately formed cushion comprising an envelope whose upper side and edge portions comprise a finish fabric, said envelope being provided with rudimentary skirts at its lower

corners, and cushioning means stuffed with- 15 in said envelope comprising a supporting frame and a spring structure mounted thereon, said cushion being mounted with the frame of said spring structure supported on the seat frame and said rudimentary skirts 20 being tacked in said rabbet, the fabric of said envelope extending between the seat frame and the frame of the cushion structure; and a finishing guimpe concealing the tacking of said skirts.

SOLOMON KARPEN.
FRANK KASPAR.
